(57) **CLAIM**

The ornamental design for a pencil case, as shown and described.

DESCRIPTION

FIG. 1 is a front perspective view of a pencil case, showing my design.

FIG. 2 is a bottom plan view thereof.

FIG. 3 is a top plan view thereof.

FIG. 4 is a left side elevation view thereof.

FIG. 5 is a right side elevation view thereof.

FIG. 6 is a front elevation view thereof.

FIG. 7 is a rear elevation view thereof.

FIG. 8 is a front perspective view of the pencil case of FIG. 1 wherein a zipper of the pencil case is opened and the pencil case is extended.

FIG. 9 is a rear perspective view of the pencil case of FIG. 1 wherein the zipper of the pencil case is opened and the pencil case is extended.

FIG. 10 is a perspective view of the pencil case of FIG. 8 wherein a cover of the pencil case is opened; and,

FIG. 11 is another perspective view of the pencil case of FIG. 8 wherein another cover of the pencil case is opened. The broken lines in the drawings depict environmental structure and boundaries and form no part of the claimed design.
